UNITED STATES PATENT OFFICE.

JEROME B. PRUITT, OF TEMPLE, TEXAS.

DRIFTING VALVE.

Application filed October 9, 1922, Serial No. 593,298. Renewed July 13, 1927.

This invention comprehends the provision of an automatic drifting valve for locomotives, by means of which steam is admitted to the cylinders subsequent to the closing of the throttle, and the valve automatically closed subsequent to the opening of the throttle, or when the locomotive is at rest, the invention having for one of its primary objects, to prevent the admittance 10 of air to the super-heater (not shown) of the locomotive.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:—

Figure 1 is a diagrammatic view of a locomotive equipped with the device forming the subject matter of the present invention.

Figure 2 is a sectional view through the device showing the normal position of the piston valve and its associated parts.

Figure 3 is a similar view, showing the position of this valve when steam is being admitted to the cylinders while drifting.

Figure 4 is a sectional view taken on line 4—4 of Figure 3.

Figure 5 is a sectional view taken on line 5—5 of Figure 3.

The device forming the subject matter of the present invention is adapted to be located in any convenient point on the locomotive, preferably a point adjacent the boiler A. The device comprises a frame-like support 10 which includes a base 11, the latter being extended an appreciable distance beyond the body 10. Arranged upon the base 11 and positioned within the frame-like support 10 is a valve case 12, in which operates a balance piston valve 13. The stem of this valve is indicated at 14, and projects through the top of the cylinder, and has associated with the upper end thereof a governor 15. The weighted arms 16 of the governor are pivotally associated at a suitable point in their length, with brackets 17 which are supported upon a beveled

gear 18 loosely mounted upon the valve stem 14, and operating on roller bearings 19 to minimize friction.

The gear 18 is of course arranged directly above the cylinder 12, and meshes with a gear 20 arranged at one side of the cylinder 12 and fixed upon a shaft 21 rotated in a manner to be hereinafter described. The shaft 21 is journaled in suitable bearings 22 and 23, the former being associated with an upright 10 supported by the base 11. Supported by the shaft 21 is a plurality of cooperating clutch disks 25, while associated with a pulley 26 is an additional clutch disk 25'. The pulley 26 is loosely mounted upon a shaft 21, but is adapted to be moved longitudinally on the shaft to move the clutch disks into operative relation, in a manner to be presently described, and when the throttle valve is closed. For this purpose, a collar 28 is slidable on the shaft 21, and is arranged directly at one end of the pulley 26, and the collar is carried by one end of a clutch lever 29, which is fulcrumed at its lower end as at 30.

Leading from the boiler A to the valve case 12 is a steam supply pipe 31, and arranged directly beneath this pipe, leading from the cylinder 12 to the locomotive cylinders 32 is an outlet pipe 33. The pipes 31 and 33 are approximately two and one-half inches in diameter, so as to supply the cylinders 32 with just enough steam when the locomotive is drifting. Arranged at one side of the supporting frame-like structure 10 is a small cylinder 34, and this cylinder communicates with the valve case 12 by means of a small pipe 35, which leads from the valve case 12 adjacent the bottom thereof and enters one end of the cylinder 34, the latter being arranged substantially at a right angle to the valve case 12.

Operating in the cylinder 34 is a piston 36, the piston rod 37 thereof sliding through the opposite end of the cylinder and connected as at 38 with the clutch lever 29. Consequently, steam from the valve case 12 is conveyed to the cylinder 34 when the throttle valve is opened, the said steam entering the cylinder 12 from the cylinders of the locomotive, and said steam admitted to the cylinder 34 actuates the piston 36 to normally hold the clutch disks 25 and 25' disengaged.

In practice, the balanced piston valve normally occupies a position illustrated in Figure 2 in which position communication between the inlet pipe 31, and the outlet pipe 33 is cut off. With the valve in this position, the same steam which is admitted to the cylinders of the locomotive, by reason of the fact that the throttle valve is opened is also admitted to the cylinder 12, passing through the pipe 35 into the cylinder 34. The piston 36 is forced to the position illustrated in Figure 2 under such conditions, and consequently, the clutch lever is shifted away from the pulley 26, thereby tensioning the spring 40 as the pulley 26 and its associated clutch disks 25' move away from the co-operating disks 25, thereby disengaging the clutch. The pulley 26 is continuously rotated while the locomotive is in motion, by means of a belt 41, which is trained over the pulley 26, and also over a pulley wheel 42, fixed to the adjacent axle 43 of the locomotive. Now, when the throttle valve is closed, and the locomotive allowed to drift, the steam in the cylinder 34 is released therefrom, bleeding through the pipe 35, with a result, that the spring 40 shifts the pulley 26 in the proper direction upon the shaft 21 to engage the clutch, thereby rotating the shaft 21. The gear 20 carried by this shaft meshes with the gear 18 to rotate the latter, and incident to the rotation of the last mentioned gear, the governor is put in operation which automatically lowers the valve 13 to the position which it occupies in Figure 3. In this position of the valve, communication between the inlet pipe 31 and the outlet pipe 33 is established, and consequently as long as the valve 13 occupies the position just mentioned, a sufficient quantity of steam will be conveyed from the boiler to the cylinders of the locomotive for the purpose above mentioned. When the throttle valve is again opened or when the engine is drifting, the valve 13 remains in its lowermost position

since steam is cut off from the cylinder 34. It will be noted that the gears 18 and 20 operate in a crank case which is arranged exteriorly of the valve case 12, this crank casing being indicated at 45 and supplied with a quantity of oil to keep the parts operating therein properly lubricated.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

In a mechanism of the character described, a valve case having a steam inlet port and a steam outlet port, a piston valve arranged to reciprocate in said case, and including a stem slidable through an opening in the top thereof, a gear surrounding said stem, a shaft arranged at a right angle to said valve case and mounted for rotation, a gear supported by said shaft and meshing with the first mentioned gear, a pulley journaled on said shaft, cooperating clutch members carried by the shaft and pulley respectively, a pivoted clutch lever connected with said pulley for moving the latter in a direction to disengage said clutch members, a small cylinder communicating with said valve case, a piston operating in said cylinder and connected with said clutch lever, a spring surrounding said shaft for moving the pulley in a direction to cause said clutch members to engage, and a governor including pivotally mounted members cooperating with the stem of said valve for moving the latter to a position to establish communication between the inlet and outlet ports as and for the purpose specified.

In testimony whereof I affix my signature.

JEROME B. PRUITT.
